CLAIM

The ornamental design for an enclosed pest control device, as shown and described.

DESCRIPTION

FIG. 1 is a top plan view of an enclosed pest control device showing my new design;

FIG. 2 is a side elevational view thereof;

FIG. 3 is a front elevational view thereof;

FIG. 4 is a perspective view thereof;

FIG. 5 is a top plan view of a second embodiment of the enclosed pest control device;

FIG. 6 is a side elevational view of the second embodiment;

FIG. 7 is a front elevational view thereof; and,

FIG. 8 is a perspective view thereof.

The rear elevational views are mirror images of the front elevational views shown in FIGS. 3, 7 the side elevational views are not shown are mirror images of the side elevational views shown in FIGS. 2, 6 and the bottom of each embodiment is plain and unornamented.
